UNITED STATES PATENT OFFICE

1,999,500

TRUSSSED CULVERT

Firman L. Carswell and Otto W. Schmidt,
Kansas City, Mo.

Application May 14, 1934, Serial No. 725,564

14 Claims. (Cl. 61—16)

This invention relates to culverts and particularly those of the larger sizes that are employed in erecting large subterranean drainage channels or arch bridges, and the primary object of the invention is to provide such a structure wherein is embodied reenforcing means for the sheet of corrugated metal wall that serves to support the latter in a way which will preclude collapse and that will combine with the inherent strength of the wall itself in maintaining it in position after filling over.

Another object of this invention is to provide a trussed culvert having unique structural features for carrying out the aforementioned broader objects, and further, having parts that combine in an admirable way with culvert parts now produced by the applicants and disclosed in United States Letters Patent No. 1,964,313, issued June 26, 1934.

Where extensive road work is being done in territories requiring a large amount of drainage, cost of erecting concrete or steel bridges and installing concrete or masonry culverts has been found to be a factor of great importance.

This invention contemplates trussed culverts that are strong, inexpensive, quickly installed, highly efficient, and may be embodied in the form illustrated in the accompanying drawings, wherein:

Figure 1 is a side elevation of a culvert made in accordance with this invention.

Fig. 2 is a top plan view of the same.

Fig. 3 is a vertical, cross section through the culvert in position on a foundation.

Fig. 4 is a fragmentary, enlarged, detailed, sectional view through a part of the culvert wall at the point of connection between the uppermost span beams, one of the purlins and the wall.

Fig. 5 is a similar section taken on line V—V of Fig. 4.

Fig. 6 is a detailed view of one of the gusset brackets entirely removed from the culvert.

Fig. 7 is a vertical, transverse, sectional view through a culvert made to embody a modified form of the invention.

Fig. 8 is a condensed, longitudinal section through the same.

Fig. 9 is a detailed perspective view of a portion of one of the sectional spans employed in this form.

Fig. 10 is an enlarged, detailed, sectional view taken on line X—X of Fig. 7.

Fig. 11 is a similar view taken on line XI—XI of Fig. 7, and,

Fig. 12 is a similar view taken on line XII—XII of Fig. 7.

Heretofore it has been unwise to construct metal culverts to accommodate wide streams or to serve as mediums of drainage where large volumes of water are to be carried off through rainy seasons. There has been a need for a strong, large culvert which would not only unobstructedly span the flow channel required, but would be sufficiently strong to support the great weight to which it is subjected after the fill has been thrown across the culvert wall. Combining a truss with the well known corrugated sheet metal wall that is formed to present an arch instead of a circular type culvert has proven satisfactory and there are several forms of the culvert contemplated by this invention that might be employed to accomplish the result desired and to suit conditions in different locations.

One preferred embodiment of this invention comprises a frame or bottom member 10 that is planar and includes two spaced-apart, preferably parallel, longitudinal side rails made up of a relatively wide channel 12, underlying a comparatively narrow channel 14, into which is fitted the longitudinal edges of wall 16 which is arched above one side of frame 10 to form a flow channel having a flat bottom. Transverse tie bars 18 join channels 12 and carry a depending apron 20 which acts as a retarding member for the water passing through the culvert so that the floor of the channel will always be maintained level with the open frame 10 because of the deposition of silt, sand, or any substance that might be carried in suspension by the flowing water.

Channels 12 have their side walls downturned, as shown in Fig. 2, and may rest upon suitable foundations 22 built for the purpose. Channels 14 have their walls extending upwardly and embrace wall 16 to preclude its lateral movement in either direction. Aprons 20 may have outwardly angled wings 24 at each end thereof and adjacent each corner of the culvert which precludes washing around any part of this culvert structure.

Arched wall 16 is trussed through the use of an overlying reenforcing skeleton work made as illustrated. This truss comprises a series of spans, each of which has a plurality of beams 23 arranged in end-to-end relation and supported upon channels 12 with wall 16. Each of beams 23 practically contacts wall 16 at a mid-point intermediate its ends and at such point extends tangentially thereto. Thus the ends of beams 23 are spaced apart from wall 16 at their abutting ends and at these points there is provided a

number of purlins 30 which extend longitudinally along wall 16 between the spans and the arched wall 16. Purlins 30 are preferably channel irons and are riveted or otherwise rigidly secured as at 32 directly to wall 16. The distance between the abutting ends of beams 28 and the thickness of purlins 30 is substantially the same and these purlins may be continuous from end to end of the culvert or may extend from one span to the other, as illustrated.

In order to permit assembly of this trussed culvert on the job after the parts thereof have been shipped from the factory, it is preferable to provide a specially formed gusset bracket 34 which not only joins together beams 28, but secures purlins 30 rigidly in position. Bolts or analogous means 36 form connection between beams 28 and gusset 34 and these gussets may be riveted as at 38 directly to purlins 30, if such is desired.

This truss forms a complete rigid network above arched wall 16 and rests directly upon the same longitudinal side rails of frame 10 as the wall. The positioning of such a truss not only precludes washing of the earth from around arched wall 16, but serves as a medium for strengthening the arched wall.

The culvert illustrated in Figs. 7 to 12 inclusive embodies a modified form of the invention. The basic structural features, however, are the same as those illustrated and described with respect to the form shown in Figs. 1 to 6 inclusive, in that foundation work 50 is provided along the longitudinal sides of the flow chamber which is created by the arched corrugated wall 52. Relatively wide channels 54 are mounted upon foundations 50 and the narrow channels 56 are associated therewith so that the upstanding sides may receive the longitudinal edges of arcuate wall 52. Tie angles 58 interconnect channels 54 and the depending apron 60 is attached to each of the said tie members 58.

In creating the reenforcing truss in this form of culvert, the same should be made up of a series of arcuate, transverse spans 62, each having a plurality of sections 64 of inverted, U-shaped cross sectional contour and with the adjacent edges in telescoped relations as illustrated in Figs. 7, 8, 10 and 11. One end of each section 64 may be reduced as at 66 so as to enter the adjacent section and a hole 68 is formed in the base of each section 64 near each end thereof. The width of section 64 making up spans 62 should be such as to allow the free edges thereof to lie within one of the inwardly arched corrugations formed by arched wall 52. This wall 52 is made up of a number of sections which overlap and the overlapping margins of the sections extend transversely over the wall 52.

Overlapping margins 70 are clearly illustrated in Figs. 10 and 11 and the manner in which one of the spans 62 forms a cover or supplementary seal for the joint is also observed. The lower ends of each span 62 are associated with either channels 54 or 56 so that the weight is taken by foundations 50 and to complete the supporting association with wall 52, there is provided a number of tie members in the form of bolts 72, which not only extend through the overlapped ends of sections 64, but also through wall 52. Suitable openings may be pierced in wall 52 where needed and holes 68 of section 64 complete the tie structure.

Internal purlins 74 extend longitudinally along wall 52 and against the inner side thereof at substantially right angles to the spans 62 and

wherever spans and purlins intersect, there should be a bolt 72 which extends through the purlin at this point. This relation of parts is illustrated in Fig. 10. The ends of each purlin 74 are cut at an angle as shown at 76 and since the purlin extends along the flow channel in the normal direction of travel of the water, it is obvious that no resistance will be set up thereby. So disposing spans and purlins 62 and 74 respectively insures a positive rigid connection between all parts of the culvert and likewise lends rigidity to the structure as a whole. Purlins 74 may be made in sections to that the length of the culvert need not be the length of the purlin and the sections 64 of spans 62 are interchangeable and relatively short so that in shipping there is a decided advantage because of the reduction in size of parts.

In installations requiring spans of from fifteen to twenty-five feet, this form of culvert is exceptionally useful and takes the place of more expensive, reinforced concrete bridges.

Having thus described the invention, what is claimed as new and desired to be secured by Letters Patent is:

1. A culvert of the character described comprising a pair of spaced-apart, longitudinal side rails; an arched wall having its longitudinal edges resting upon the said side rails; a reenforcing truss spanning the space between said side rails and overlying said arched wall; and means rigidly interconnecting said truss and arched wall, said truss being carried by the side rails that supports the arched wall.

2. A culvert comprising, in combination, an open frame having longitudinal side rails; tie members to maintain the said side rails in spaced relation; an arched wall closing one side of the frame and overlying the same with its longitudinal edges resting upon said side rails; and a truss 40 overlying said arched wall, rigidly secured thereto and mounted upon the side rails.

3. A culvert comprising an open frame having longitudinal side rails disposed in spaced relation; a wall overlying one side of said frame with its longitudinal edges resting upon the side rails; and a truss mounted on the said side rails and extending over said wall, said truss comprising a series of spans and means rigidly joining the spans and said wall at spaced-apart points 50 along the length of the former.

4. A culvert comprising an open frame having longitudinal side rails disposed in spaced relation; a wall overlying one side of said frame with its longitudinal edges resting upon the side rails; and a truss mounted on the said side rails and extending over said wall, said truss comprising a series of spans extending transversely over said arched wall, a plurality of purlins interconnecting said spans and extending longitudinally along the wall, and means rigidly interconnecting said purlins and wall.

5. A culvert comprising an open frame having longitudinal side rails disposed in spaced relation; a wall overlying one side of said frame with its longitudinal edges resting upon the side rails; and a truss mounted on the said side rails and extending over said wall, said truss comprising a series of spans extending transversely over said arched wall, a plurality of purlins extending longitudinally along the wall and transversely of the said spans, and brackets joining the said spans and purlins at their points of intersection.

6. A culvert comprising an open frame having longitudinal side rails disposed in spaced rela-

tion; a wall overlying one side of said frame with its longitudinal edges resting upon the side rails; and a truss mounted on the said side rails and extending over said wall, said truss comprising a series of spans extending transversely over said arched wall, a plurality of purlins extending longitudinally along the wall and transversely of the said spans, and brackets joining the said spans and purlins at their points of intersection, 10 the said spans each comprising a plurality of beams having abutting ends at the points of intersection with the said purlins.

7. In a culvert of the kind described, a frame having side rails; an arched wall closing one side 15 of the frame and extending thereabove; and a truss mounted on the side rails and extending over the said wall comprising a series of spans each having a plurality of rectilinear beams arranged in end-to-end relation, and a plurality 20 of purlins interconnecting said spans and wall at the abutting ends of the beams of said spans, the width of said purlins being substantially the same as the distance between the said wall and spans at said points of interconnection, said 25 beams being tangent to the said wall intermediate the ends of the former.

8. A culvert comprising an arched wall forming a flow channel; and a reenforcing truss secured to said wall comprising a series of arched spans 30 extending over said wall in supporting relation thereto, and longitudinally extending purlins within said flow channel against said wall, said spans and purlins being secured together at the respective points of intersection.

35 9. A culvert comprising an arched wall forming a flow channel; and a reenforcing truss in supporting relation with said wall comprising a series of arched spans extending transversely over said wall, longitudinally extending purlins 40 within said flow channel along the inner side of said wall, and tie members securing together the spans, purlins and wall at the respective points of intersection of the spans and purlins.

10. A culvert comprising an arched wall forming a flow channel; and a reenforcing truss in 45 supporting relation with said wall comprising a series of arched spans, each comprising a plurality of telescoped sections, extending transversely over said wall, longitudinally extending purlins 50 along the inner side of said wall, and tie members securing together the spans, purlins and wall at the respective points of intersection of the spans and purlins, said tie members serving to also secure together the telescoped ends of the 55 span sections which overlie the purlins.

11. A culvert comprising an arched wall form-

ing a flow channel and including a number of overlapping wall sections having the overlapped margins thereof extending transversely of the flow channel; and a reenforcing truss comprising a series of arched, transversely extending spans over the said wall, said spans being substantially inverted, U-shaped in cross section and having their edges against the outer face of the said wall, and means for securing together the said spans and wall.

12. A culvert comprising an arched wall forming a flow channel and including a number of corrugated, overlapping wall sections having the overlapped margins thereof extending transversely of the flow channel; and a reenforcing 15 truss comprising a series of arched, transversely extending spans over the said wall, said spans being substantially inverted, U-shaped in cross section and having their edges against the outer face of the said corrugated wall and respectively 20 within one of the inwardly curved corrugations, and means for securing together said spans and wall.

13. A culvert comprising an arched wall forming a flow channel and including a number of corrugated, overlapping wall sections having the overlapped margins thereof extending transversely of the flow channel; and a reenforcing truss comprising a series of arched, transversely extending spans over the said wall, said spans being 30 substantially inverted, U-shaped in cross section and having their edges against the outer face of the said corrugated wall and respectively within one of the inwardly curved corrugations, and means for securing together said spans and wall, 35 certain of said inverted U-shaped spans overlying the overlapping margins of the wall substantially throughout their lengths.

14. A culvert comprising an arched wall forming a flow channel and including a number of corrugated overlapping wall sections having the overlapped margins thereof extending transversely of the flow channel; and a reenforcing 40 truss comprising a series of arched, transversely extending spans over the said wall, said spans 45 being substantially inverted, U-shaped in cross section and having their edges against the outer face of the said corrugated wall and respectively within one of the inwardly curved corrugations, and means for securing together said spans and 50 wall, said spans each comprising a plurality of telescoped sections, the said securing means also serving to lock together the telescoped portions of the said sections.
